UNITED STATES PATENT OFFICE.

JOHN E. CHALMAN, OF CHICAGO, ILLINOIS.

HEMMER FOR SEWING-MACHINES.

1,305,253.

Specification of Letters Patent. Patented June 3, 1919.

Application filed August 3, 1917. Serial No. 184,269.

To all whom it may concern:

Be it known that I, JOHN E. CHALMAN, a citizen of the United States, residing at Chicago, in the county of Cook, State of Illinois, have invented certain new and useful Improvements in Hemmers for Sewing-Machines, of which the following is a description, reference being had to the accompanying drawing and to the figures of reference 10 marked thereon.

The invention relates to new and useful improvements in folders for sewing machines and more particularly a folder for turning underneath an edge of fabric to 15 form a hem therein.

An object of the invention is to provide a folder of the above character having a folding recess for forming a hem fold in the fabric wherein the inner wall of the folding 20 recess is free from projecting portions extending beyond the stitching line, whereby the folder may be used for completing a circular hem.

A further object of the invention is to 25 provide a folder of the above character wherein a section of the folder at the delivery end thereof is capable of being shifted or moved so as to relieve the initially formed hem from undue friction as it passes through 30 the folder in the completing of the circular hem, and to create sufficient space for the removal of the completed hem.

A still further object of the invention is to 35 provide a folder of the above character wherein the movable section may be shifted at the will of the operator, and without stopping the stitching mechanism.

In the drawings, which show by way of 40 illustration one embodiment of the invention;

Figure 1 is a plan view showing a portion of a sewing machine with my improved folder applied thereto;

Fig. 2 is a front view of the same;

Fig. 3 is a sectional view through the 45 folder on the line 3-3 of Fig. 1;

Fig. 4 is a view similar to Fig. 3, but showing the movable section of folder withdrawn;

Fig. 5 is a perspective view of the folder 50 with the movable section thereof withdrawn;

Fig. 6 is a sectional view on the line 6-6 of Fig. 4;

Fig. 7 is a detail in perspective showing a 55 treadle connection for separating the sections of the folder;

Fig. 8 is a perspective view showing on a small scale a circular hem such as is adapted to be formed by my improved folder.

The invention broadly consists in a folder 60 for sewing machines having a folding recess for turning underneath the edge of a fabric to form a hem. This folding recess is formed by vertical guiding walls carried by the base of the folder, one of said guiding 65 walls extending above the other and being provided with a turning flange so that the fabric to be folded may be led into the recess at the top and be turned underneath. The inner wall is free from portions projecting 70 beyond the line of stitches, so that the initially stitched part of the hem may pass through the folder without being obstructed thereby. A section of the folder at the delivery end thereof is made movable and this 75 is controlled by the operator at will without stopping the stitching mechanism, so that said movable section may be withdrawn to permit the initially formed portion of the hem fold to pass through the folder for 80 completing a circular hem, and to create sufficient space to permit the completed hem to be readily withdrawn from the folder.

Referring more in detail to the drawings, I have shown my invention as applied to a 85 sewing machine having a work arm 1 which is carried by a standard 2. The material is held on the work arm by a presser foot 3. The machine is provided with a stitching mechanism, the needle of which is indicated 90 at 4. The stitching mechanism is adapted to produce a straight line of stitching and the stitching line is indicated at x-x in Fig. 1.

The material to be stitched is led through 95 my improved folder, which consists of a base plate 5, on which is mounted a vertical wall or guiding member 6. This vertical wall is carried by a shank 7 having slots 8-8 adapted to receive screws 9-9 whereby 100 said vertical wall or guiding member may be adjusted and fixed in adjusted positions. The base plate also carries a second vertical wall or guiding member 10 which is secured thereto by screws 11-11. These two walls 105 are fixed relative to each other, and to the stitching line during the normal operation of the machine. The vertical wall 6 is concave on its inner face and is provided with an overhanging flange 12 at its upper end. 110 The vertical wall 10 is also slightly concave at its inner face and terminates some

distance below a horizontal plane containing the overhanging flange so that there is a space between the upper end of the wall 10 and the flange 12.

- 5 The invention is particularly adapted for turning a hem fold for the forming of a circular hem. In Fig. 8 of the drawing I have shown a fabric at *f* having a hem formed therein. The edge of the fabric is 10 continuous, and the hem extends all the way around, thus forming what I term a circular hem. The material is led into the folder underneath the flange 12 and the edge portion is folded around underneath to form a 15 hem, as shown in Fig. 3 of the drawings. The needle passes downwardly through the fabric and through the edge of the hem as clearly indicated in Fig. 8. It will be noted that the initially stitched part of the hem 20 must pass through the folder in the completing of the circular hem. The vertical wall 10 is free from any projection extending across the stitching line indicated at *x*—*x* in Fig. 1, and, therefore, this circular hem 25 is free to pass through the folder at the receiving end thereof without the parts of the folder obstructing the same, either by binding the finished hem or by engaging the stitches formed in the hem. The folder is 30 provided with a movable section at the delivery end thereof. This movable section is indicated at 13 in the drawings. Said movable section includes a vertical wall 14, which forms one portion of the delivery end of the 35 folder and also forms a continuation of the wall 10. The supporting shank 15 of the movable section 13 is secured to a bar 16 by means of a bolt 17. Said movable section of the folder has a forwardly projecting 40 base plate 18, which extends underneath the wall 6 of the folder. The inner end 19 of this movable section is adapted to engage a shoulder 20. The bar 16 is normally pressed to the right by means of a spring 21. This 45 spring bears against a collar 22 fixed to the end of the bar and a shoulder 23 carried by the supporting bracket 24 on which the folder is mounted. The base plate 5 for the 50 folder is attached to this bracket 24 by means of screws 26, 26.

The bar 16 is moved to the left against the tension of the spring 21 by a rock lever 27 pivoted at 28 to the standard 2 of the machine. Said rock lever is formed with a 55 bracket 29 adapted to make contact with the end of the bar. A spring 30 normally presses the upper end of the rock lever to the right. A treadle 31 (see Fig. 7) is connected by a suitable flexible connection 32 to the rock lever.

In the operation of my device, the fabric is inserted in the folder in the manner shown in Fig. 3. As the fabric passes through the folder, the hem fold is formed and directed 60 underneath the presser foot, and the needle

will enter the fabric and the hem fold and stitch the same. The initially stitched part of the hem fold when it reaches the receiving end of the folder will freely pass into the same. At this time the operator without 70 stopping the machine will press the treadle which shifts the movable section of the folder, to the position shown in Fig. 4. This opens the delivery end of the folder, so as to permit the finished hem to pass readily 75 therethrough without binding or undue friction. Furthermore, by this shifting of the movable section away from the flange 12, I am able to readily withdraw the finished 80 hem from the folder, by lifting said finished portion of the hem above the top of the vertical walls 10 and 13 and then moving the hem sidewise. There is ample room between the top of these vertical walls and the flange 12 at each end of the folder to permit this 85 withdrawal.

It is obvious that minor changes in the details of construction and the arrangement of the parts may be made, without departing from the spirit of my invention as set forth 90 in the appended claims.

What is claimed is:

1. A folder for sewing machines for stitching circular hem, said folder having spaced walls forming a hem folding recess, said walls being shaped so as to be free from projecting portions extending between the hem and the body of the material and crossing the stitching line, whereby the initial 95 stitched portion of the hem may pass 100 through the folder for the completing of the circular hem.

2. A folder for sewing machines having a hem-folding recess, the inner wall of which is free from projecting portions extending beyond the stitching line, whereby a circular 105 hem may be completed and stitched, said folder having a movable section capable of being shifted to permit the initially stitched portion of the hem to pass through the 110 folder.

3. A folder for sewing machines including spaced inner and outer vertical walls having their inner faces concaved and forming a 115 hem-folding recess, said walls being fixed relative to each other at the receiving end of the folder, the inner wall of said folder at the delivery end thereof being movable away from the outer wall to permit the initially 120 stitched portion of the hem to freely pass through the folder.

4. The combination with stitching mechanism including a needle, a folder, said folder having spaced inner and outer vertical walls forming a hem-folding recess, the outer wall having an overhanging flange located above and spaced from the inner wall, said inner wall at the receiving end of the folder being free from projecting portions extending beyond the stitching line, whereby the initially 125 130

stitched portion of the hem may pass through the receiving end of the folder.

5. The combination with stitching mechanism including a needle, of a folder, said folder having spaced inner and outer vertical walls forming a hem folding recess, the outer wall having an overhanging flange located above and spaced from the inner wall, said inner wall at the receiving end of the folder being free from projecting portions extending beyond the stitching line, whereby the initially stitched portion of the hem may pass through the receiving end of the folder, said folder at the delivery end thereof having a movable section capable of being shifted laterally to permit the initially stitched portion of the hem to freely pass through the delivery end of the folder.
10. The combination with stitching mechanism including a needle, of a folder, said folder having spaced inner and outer vertical walls forming a hem folding recess, the outer wall having an overhanging flange located above and spaced from the inner wall, said inner wall at the receiving end of the folder being free from projecting portions extending beyond the stitching line, whereby the initially stitched portion of the hem may
15. The combination with stitching mechanism including a needle, of a folder, said folder having spaced inner and outer vertical walls forming a hem folding recess, the outer wall having an overhanging flange located above and spaced from the inner wall, said inner wall at the receiving end of the folder being free from projecting portions extending beyond the stitching line, whereby the initially stitched portion of the hem may
20. The combination with stitching mechanism including a needle, of a folder, said folder having spaced inner and outer vertical walls forming a hem folding recess, the outer wall having an overhanging flange located above and spaced from the inner wall, said inner wall at the receiving end of the folder being free from projecting portions extending beyond the stitching line, whereby the initially stitched portion of the hem may
25. The combination with stitching mechanism including a needle, of a folder, said folder having spaced inner and outer vertical walls forming a hem folding recess, the outer wall having an overhanging flange located above and spaced from the inner wall, said inner wall at the receiving end of the folder being free from projecting portions extending beyond the stitching line, whereby the initially stitched portion of the hem may

pass through the receiving end of the folder, said folder at the delivery end thereof having a movable section capable of being shifted laterally to permit the initially stitched portion of the hem to freely pass through the delivery end of the folder, and means for shifting said movable sections at the will of the operator, and without stopping the stitching mechanism.

7. A folder for sewing machines including spaced inner and outer vertical walls having their inner faces concaved and forming a hem-folding recess, said walls being fixed relative to each other at the receiving end of the folder, the inner wall of said folder at the delivery end thereof being movable away from the outer wall to permit the initially stitched portion of the hem to freely pass through the folder, and means for shifting said movable section at the will of the operator and without stopping the stitching mechanism.

In testimony whereof, I affix my signature, in the presence of two witnesses.

JOHN E. CHALMAN.
